DESIGN FOR A COMBINED HOLDER AND PLANT POT

Harriet R. Cutter, New York, N. Y.

Application March 14, 1939, Serial No. 83,574

Term of patent 3½ years

To all whom it may concern:

Be it known that I, Harriet R. Cutter, a citizen of the United States, residing in New York city, in the county of New York and State of New York, have invented a new, original, and ornamental Design for a Combined Holder and Plant Pot, of which the following is a specification, reference being had to the drawing, forming a part thereof.

The figure of the drawing is a perspective view of a combined holder and plant pot, showing my new design.

I claim:

The ornamental design for a combined holder and plant pot, substantially as shown.

HARRIET R. CUTTER.
